R. J. O. SIMPSON

CASE FOR MEASURING TAPES AND THE LIKE

Filed April 8, 1926

FIG. 1

FIG. 4

FIG. 3

FIG. 5

Inventor

Robert J. O. Simpson

By Dee's Speaff.
Attorney

UNITED STATES PATENT OFFICE.

ROBERT J. O. SIMPSON, OF ATHOL, MASSACHUSETTS, ASSIGNOR TO THE L. S. STARRETT COMPANY, OF ATHOL, MASSACHUSETTS, A CORPORATION OF MASSACHUSETTS.

CASE FOR MEASURING TAPES AND THE LIKE.

Application filed April 8, 1926. Serial No. 100,535.

Measuring tapes have been supplied in both steel and leather cases, and it has been proposed heretofore to arrange the tape in a steel case with a leather or imitation leather cover.

5 The problem with any covered case is to fit the cover snugly to the case in such a manner that it will positively remain fitted under the varying conditions of use of the tape.

My present invention is directed to this 10 general problem and aims to provide a simple and efficient means for obtaining this result. To this end, I construct the tape case in the form of a pair of metallic discs, having peripheral flanges disposed to abut each other 15 and define a compartment within which the tape drum winding spring and tape are contained. The leather or other covering material is also cut in the form of a pair of discs which are held centrally to the case members 20 by the usual flanged washers which afford bearing for the usual push button and winding handle of the tape, the peripheral edge of each covering disc being turned over upon the flange of the case member which it covers.

25 The flanges of the case members are interrupted between their ends by cut-outs which, when the case members are abutted oppose one another and define a single delivery opening through which the tape may be projected and retracted. Each case flange is also provided with a circumferential groove within 30 which the peripheral edges of the covering discs are confined by a concavo-convex split clamping ring applied exteriorly thereto, a portion of the edge of each covering disc being drawn into said opposing cut-outs of the case flanges for greater security. The 35 ends of the split clamping ring are bent under the case flanges at said cut-outs, and are clamped in this position by the bendable flanges of the usual eyelet which lines and 40 finishes the tape delivery opening defined by said cut-outs. This construction provides a quick and convenient method of assembly, as 45 well as a neat and attractive product in which the covering material is positively held in place at all times and under all conditions of use of the tape.

The construction and method of assembling 50 my tape is described and illustrated in the accompanying specification and drawings, and the characteristic features of novelty are particularly pointed out in the appended claims.

In the drawings:

Fig. 1 is a face view of a tape case in accordance with my invention.

Fig. 2 is an edge view thereof.

Fig. 3 is a detail view of one of the case members particularly showing the split 60 clamping ring and securing eyelet.

Fig. 4 is a section on the line 4—4 of Fig. 3.

Figure 5 is an enlarged fragmentary sectional view of the case.

I have indicated at 1 a pair of complementary case sections having peripheral flanges 2 adapted to be abutted against each other to define an enclosed compartment within which the tape, tape drum, and tape retraction spring are mounted in the usual manner. Each case section is centrally apertured to receive respectively the usual push button and tape winding handle with which tapes of this type are generally equipped, and these apertures are provided with the usual 75 flanged washers 3 to afford bearing for said parts.

Each case flange 2 is provided with a circumferentially extending groove 4, and each flange is also interrupted between its ends by 80 the cut-outs 5 which when the case sections 1 are assembled, lie opposite each other and define the tape delivery opening 6 of the case.

As contemplated herein, the case sections 1 are covered by a pair of leather or other 85 covering discs 7 which are held centrally to the faces of the case sections by the flanged washers 3. The peripheral edges of the covering discs are bent over the flanges 2 of the case sections and are clamped in the relation shown by a concavo-convex split clamping ring 8, which is drawn over both flanges with its edges entered within and forcing the covering material 7 into said grooves 4 of the flanges, as clearly appears in Fig. 4. The 90 ends of the ring 8 are down-turned as indicated at 9, Fig. 3, and hooked under the flanges 2 at the cut-outs 5, the covering material preferably being slitted at these points to permit it to be bent into said cut-outs and 95 clamped by said hooked ends 9.

The parts are maintained in this relation by means of the usual metallic eye 10 which lines and finishes the delivery opening of the case. This eye has a pair of oppositely disposed depending tongues 11, which are adapted to be bent against the down-turned 100 hooked ends 9 of the clamping ring to prevent

relative movement of the ring on the flanges of the case sections. The clamping band or ring 8 itself is of substantial width; i. e., it is sufficiently wide to engage and clamp the marginal edges of the cover pieces over the peripheral wall of the tape case as well as to overlie such edges and conceal them from view, thus adding to the neat and attractive appearance of the tape case.

10 Various modifications in the construction and assembly of my device may obviously be resorted to if within the limits of the appended claims.

What I therefore claim and desire to secure by Letters Patent is:

1. In a case, opposing case sections, having peripheral flanges interrupted between their ends by cut-outs, a cover piece applied to each case section with its marginal edge overlying the flange of the case section with a portion of said edge drawn into the cut-out of said flange, and a clamping member disposed circumferentially about said case sections and clamping the marginal edges of the cover pieces against said flanges, the ends of said clamping member being hooked beneath said flanges at said cut-outs, and an eye-piece fitted into the opening defined by said cut-outs and formed to engage the hooked ends of said clamping member to prevent movement of the clamping member relative to said case flanges.

2. In a case, opposing case sections having peripheral flanges interrupted between their ends by cut-outs and each flange having a circumferentially extending groove, a cover piece secured to the outer face of each case section with its marginal edge overlying the flanges of the case section with a portion of said edge drawn into the cut-out of said flange, and a split clamping ring disposed circumferentially about said case sections and clamping the marginal edges of the cover pieces into said grooves of the flanges, the ends of said ring being hooked beneath said flanges at said cut-outs, and an eye-piece fitted into the opening defined by said cut-outs and formed to engage the hooked ends of said ring to prevent movement of the ring relative to said case flanges.

3. In a case, complementary case sections having peripheral flanges adapted to abut each other, said flanges having each a circumferentially extending groove and each flange interrupted between its ends by a cut-out, a cover piece secured to the outer face of each case section and having its marginal edge overlying the flange of the case section with a portion of said edge drawn into the cut-out of said flange, and a concavo-convex split clamping ring disposed circumferentially about said case sections and clamping the marginal edges of the cover pieces into said grooves of the flanges, the ends of said ring being hooked beneath said flanges at said cut-

outs, and an eye-piece fitted into the opening defined by said cut-outs and having depending locking tongues adapted to be bent against the hooked ends of said ring to prevent movement of the ring relative to said case flanges.

4. In a tape measure case, two shallow casing-forming members having opposing flanges provided with alined cut-outs which together define a tape delivery opening, a cover piece secured to each casing-forming member with its marginal edge overlying the flange thereof, and a clamping member disposed circumferentially about said casing-forming members in clamping relation to the marginal edges of said cover pieces, the ends of said clamping member being inserted into the tape delivery opening and hooked about the edges of said opening.

5. In a tape measure case, two shallow casing-forming members having opposing flanges provided with alined cut-outs which together define a tape delivery opening, a cover piece secured to each casing-forming member with its marginal edge overlying the flange thereof, and a clamping member disposed circumferentially about said casing-forming members in clamping relation to the marginal edges of said cover pieces, the ends of said clamping member being inserted into the tape delivery opening and hooked about the edges of said opening, and an eyelet member projecting within said opening and clamping said hooked ends in the relation indicated.

6. In a tape measure case, a pair of casing-forming members presenting a peripheral wall having a tape delivery opening, cover pieces secured to the casing-forming members with their marginal edges overlying the peripheral wall of the casing, and a clamping member disposed circumferentially about said peripheral wall in clamping relation to the edges of said cover pieces, the ends of said clamping member being inserted into the tape delivery opening and hooked about the edges thereof.

7. In a tape measure case, a pair of casing-forming members presenting a peripheral wall having a tape delivery opening, cover pieces secured to the casing-forming members with their marginal edges overlying the peripheral wall of the casing, and a clamping member disposed circumferentially about said peripheral wall in clamping relation to the edges of said cover pieces, the ends of said clamping member being inserted into the tape delivery opening and hooked about the edges thereof, and an eyelet member projecting within said opening and clamping said hooked ends in the relation indicated.

8. In a tape measure case, a casing having a peripheral tape delivery opening, cover pieces secured to the side walls of the casing

- with their marginal edges overlying the periphery of the casing, and a clamping member disposed circumferentially about said casing in clamping relation to the marginal edges of said cover pieces, the ends of said clamping member being inserted into the tape delivery opening and hooked about the edges of said opening.
9. In a tape measure case, a casing having a peripheral tape delivery opening, cover pieces secured to the side walls of the casing with their marginal edges overlying the periphery of the casing, and a clamping member disposed circumferentially about said casing in clamping relation to the marginal edges of said cover pieces, the ends of said clamping member being inserted into the tape delivery opening and hooked about the edges of said opening, and an eyelet member 20 projecting within said opening and clamping said hooked ends in the relation indicated.
10. In a tape measure case, a casing having a peripheral recess, a pair of cover pieces secured to the side walls of the casing with their marginal edges overlying the periphery of the casing, and a clamping member disposed circumferentially about the periphery of the casing and tensionally clamping the marginal edges of the cover pieces in said recess.
- 25 11. In a tape measure case, a casing having a peripheral recess, a pair of cover pieces secured to the side walls of the casing with their marginal edges overlying the periphery of the casing, a split clamping member disposed circumferentially about the periphery of the casing and tensionally clamping the marginal edges of the cover in said recess, and means frictionally engaging said clamping member for holding it in the relation indicated.
- 30 12. In a tape measure case, a casing having a peripheral recess and a tape delivery opening intersecting said recess, a pair of cover pieces secured to the side walls of the casing with their marginal edges overlying the periphery of the casing, and a split clamping member disposed circumferentially about the periphery of the casing with its ends lodged in said tape delivery opening and tensionally clamping the marginal edges of the cover pieces in said recess.
- 35 13. In a tape measure case, a casing having a peripheral recess and a tape delivering opening intersecting said recess, a pair of
- cover pieces secured to the side walls of the casing with their marginal edges overlying the periphery of the casing, a split clamping member disposed circumferentially about the periphery of the casing with its ends lodged in said tape delivery opening and tensionally clamping the marginal edges of the cover in said recess, and an eyelet disposed in said tape delivery opening and frictionally engaging the terminal ends of said clamping member for holding said member in the relation indicated.
- 40 14. In a tape measure case, a pair of casing-forming members presenting a peripheral wall having a tape delivery opening, an eyelet in said opening, cover pieces secured to the casing-forming members with their marginal edges overlying the peripheral wall of the casing, and a clamping member disposed circumferentially about said peripheral wall in clamping relation to the edges of said cover pieces, the ends of said clamping member being located adjacent the tape delivery opening and secured to the casing by means of the eyelet mounted in said opening.
- 45 15. In a tape measuring case presenting a peripheral wall having a tape delivery opening, cover pieces for said case having marginal edges overlapping said wall, and a longitudinally tensioned band of substantial width extending circumferentially about said wall in covering and clamping relation to said edges of the cover pieces.
- 50 16. In a tape measuring case presenting a peripheral wall having a tape delivery opening, an eyelet in said opening, cover pieces for said case having marginal edges overlapping said wall, and a band of substantial width applied under tension to said wall in covering and clamping relation to said edges of the cover pieces and having its ends secured by said eyelet.
- 55 17. In a tape measuring case presenting a circumferentially grooved peripheral wall having a tape delivery opening, cover pieces for said case having marginal edges overlapping said wall, and a longitudinally-tensioned band of substantial width extending circumferentially about said wall and clamping said edges of the cover pieces thereover.

In testimony whereof I affix my signature.

ROBERT J. O. SIMPSON.
